SUSPENDED ROOF CONSTRUCTION
Levi S. Longenecker, 61 Mayfair Drive,
Pittsburgh 28, Pa.
Filed May 2, 1960, Ser. No. 26,286
17 Claims. (Cl. 110—99)

This invention relates to a suspended furnace roof construction and particularly, to an improved roof assembly and part construction employed for suspending refractory tile or brick in a furnace structure.

In a high temperature furnace installation, such as here involved, refractory tile or block are mounted in a closely abutting relation for exposure to the inside furnace heat. The tile or block are supported by refractory hangers which are, in turn, supported by metal hangers and metal furnace frame members. It is important in a furnace roof or arch to facilitate the initial installation or mounting of the members thereof and particularly the tile, and to do so in such a manner as to make possible a maximum life of the roof and to also facilitate the repair and maintenance of the roof. The mounting should be such as to avoid undue stress and strain, particularly on the refractory members, to minimize the metal parts necessary without weakening the construction, to provide flexibility of installation, and to suspend or mount the refractory tile furnace-lining members of the roof in an effective sealed-off relationship with respect to each other.

It has been an object of my invention to provide an improved furnace roof or arch structure and particularly, to develop an improved roof member construction and assembly;

Another object has been to determine the factors which have heretofore given difficulty in a furnace roof construction and to meet the factors in such a manner as to solve the problem involved;

Another object of my invention has been to provide an improved method of employing and assembling furnace roof members, including refractory and metal parts thereof;

A further object of my invention has been to provide an improved refractory hanger and tile or block construction for a furnace and improved means for mounting the members in a suspended position and supporting them as a part of the furnace structure;

A still further object of my invention has been to devise furnace assembly parts which will minimize stress and strain of an arch or roof construction in its utilization and, at the same time, provide a simplified arrangement;

These and other objects of my invention will appear to those skilled in the art from the description of the specification and the showing of the drawings;

In the drawings, FIGURE 1 is a top plan fragment of a furnace roof or arch assembly constructed in accordance with my invention;

FIGURE 2 is a side view in elevation, partially in section, of and on the same scale as the structural assembly of FIGURE 1;

FIGURE 3 is an enlarged sectional fragment in elevation taken through the structure of FIGURES 1 and 2, at right angles thereto; this figure illustrates how refractory tile or block members are assembled as interfitting rows in an assembly consisting, for example, of rows A, B and C of FIGURE 1;

FIGURE 4 is an enlarged isometric view in elevation of a refractory hanger part or member employed in the construction of FIGURES 1 to 3; this figure is on the same scale as FIGURE 3;

FIGURE 5 is a front view in elevation of the refractory hanger of and on the same scale as FIGURE 4;

2

FIGURE 6 is an end or edge view in elevation of the refractory hanger of FIGURES 4 and 5 and on the same scale;

FIGURE 7 is a top plan view on the scale of and of the refractory hanger of FIGURES 4, 5 and 6;

FIGURE 8 is a horizontal section on the scale of and taken along the line VIII—VIII of FIGURE 6;

FIGURE 9 is a vertical section on the scale of and taken along the line IX—IX of FIGURE 8;

FIGURE 10 is an isometric view in elevation of a refractory tile or block part or member of FIGURE 3 and on the same scale as such figure;

FIGURE 11 is a fragmental isometric view on the scale of FIGURE 10 and of a top portion of the refractory tile or block of that figure and taken from an opposite side thereof;

FIGURE 12 is an isometric view in elevation of a metal hanger shown in FIGURE 3 and on the same scale as such figure;

FIGURE 13 is an isometric view in elevation of a metal link bar of FIGURE 3 and on the same scale as such figure;

FIGURE 13A is a horizontal section taken along the line XIII—XIII of FIGURE 13 and on an enlarged scale as to such figure;

FIGURE 14 is a transverse view, somewhat similar to FIGURE 3 but on a reduced scale, illustrating that refractory tile of a pair of adjacent rows, for example, at the center line of the roof, may be reversed or turned around, in order to provide opposite side pivot mounting of the tile as side halves of the roof are built up therefrom by working two (opposite) directions from the center line; it shows that, in such an event, where refractory tile of one row do not complement those of an adjacent row, voids between the grooves may be filled up with mortar;

FIGURE 15 is a top plan view on a slightly enlarged scale with respect to and somewhat similar to FIGURE 1, but illustrating additional rows of blocks represented by D, E, and F, and showing modifications that may be employed, for example, in a repair assembly;

FIGURE 16 is a fragmental sectional view in elevation on the scale of and taken along the line XVI—XVI of FIGURE 15;

FIGURE 17 is an isometric view in elevation on the scale of FIGURE 4, illustrating a modified refractory hanger for use in facilitating repair or replacement work in a furnace roof;

FIGURE 18 is a top plan view somewhat similar to FIGURES 1 and 15 and on the scale of FIGURE 1, illustrating a modified construction employing rows G, H and I, wherein a modified type of hanger, such as shown in FIGURE 21, may be employed;

FIGURE 19 is a fragmental side view in elevation of the construction of FIGURE 18 and on the same scale;

FIGURE 20 is a side section in elevation on the scale of and taken along the line XX—XX of FIGURE 18, showing the mounted assembly of row H thereof; and,

FIGURE 21 is an isometric view in elevation on the scale of FIGURE 12, showing a modified type of metal hanger suitable for employment in the construction of FIGURES 18 to 20; it will be noted that the modified construction of these figures represents one that may be employed in replacing a section of a furnace that has been burnt out, for example; the modification facilitates the insertion of a repair portion within the furnace roof without disturbing other portions thereof.

In FIGURES 1 to 13, inclusive, I have illustrated a roof structure 10 of my invention that is particularly suitable in the initial building of a roof. As shown in FIGURES 1 and 2, suitable support beams 11 that are normally full-length transverse roof members, constitute

spaced-apart main roof I-beams and may be mounted, set or secured in a conventional manner at their ends to form an overhead roof superstructure. Relatively short-length, spanning, cross I-beam members 12 that normally extend as longitudinal members of the roof, are shown as positioned to extend transversely across the spacing between adjacent pairs of the main or support beam members 11 and, as to an adjacent pair of support beams 11, extend in a spaced-apart relationship with each other. The cross beams 12 are assembled as groups or rows of 10 endwise-aligned members that extend longitudinally of the furnace and crosswise of the support beams 11 (see FIGURE 2) to define overhead supports for aligned rows of refractory tile or block members 26.

It will be noted that each cross beam member 12 is 15 positioned to rest at its opposite ends on the top face of one side of bottom flanges of an adjacent pair of main beams 11, in adjacency with the web portions of the main beams, and, if desired, may be tilted (raised and lowered) into and out of position about one of its ends. The 20 cross beams 12 do not require tie-down means for such ends. In accordance with my invention, the cross beam members 12 are essentially slidable along the bottom flanges of the pair of main or support beams 11. In FIGURE 1, I have illustrated two spaced-apart tile rows A and C, as defined and directly supported by metal hangers 13 in alignment on longitudinal rows of cross beam members 12, and an intermediate or alternate row B, spaced between adjacent pairs of such beam members and indirectly supported therefrom by metal link bar 30 hangers or members 16, see also FIGURE 3.

As shown particularly in FIGURES 2 and 3, each cross beam 12 carries a series of upright metal hangers 13 of somewhat rectangular shape and closed or looped frame configuration that are adapted to be slid over the ends of such cross beam and ride along and hang from its top flange in a substantially parallel and spaced relation with its web and along opposed edges of its top and bottom flanges to project therebeneath. Each hanger 13 (see also FIGURE 12) has vertically spaced-apart top and bottom, cross-connecting or link portions 13a and 13b and horizontally spaced-apart, vertically-extending, side leg or frame portions 13c and 13d, all as a part of an integral or one-piece hanger structure.

Referring particularly to FIGURE 12, each hanger 13 has position-stabilizing tab means consisting of a pair of opposed or oppositely-projecting top tabs, foot prongs or lugs 14 that project centrally-backwardly and forwardly from and on the plane of the top connecting portion 13a. The prongs 14, as shown particularly in FIGURES 1 to 3, are adapted to rest on and along the top flange of an associated cross beam member 12 and prevent the hanger 13 from swinging vertically in its suspended relationship. Again referring to FIGURE 12, each loop hanger 13 has a pair of guide shelf portions, extending lugs, prongs or feet 15 which project from one edge face of the pair of side portions 13c and 13d, adjacent the horizontal lower connecting portion 13b, but in a spaced relation therewith. As a pair, the feet 15 define side-guides for opposed sides of a refractory hanger 17, see FIGURE 3, and also as support shelves for latching end portions 16c of a metal link bar 16.

As shown particularly in FIGURE 13, each link bar 16 has a centrally-disposed, closed, rectangular, loop frame portion 16a that comprises integral horizontal top and bottom portions and side portions. The loop 16a, as shown in FIGURE 3, is adopted to latch within end-latching slot portions 19 (see also FIGURE 4) of a refractory hanger 17. Each link bar 16 also has an opposed pair of side-extending horizontally-positioned leg portions 16b that project adjacent the top portion of the center loop 16a to cooperate with and normally rest in a top clearance relation with refractory hangers 17 of adjacent row pairs, such as A and C of FIGURE 1, to support an intermediate row, such as B of the same figure.

Each arm 16b of the link bar 16 is shown as having a turned-down latching end 16c that is adapted to cooperate with or fit above sidewise-open top slots in a refractory hanger 17. It will be noted from FIGURE 3 that the ends 16c normally latch over and rest upon shelf portions 15 of the metal hangers 13. As will be noted from FIGURE 13, link bar casting 16 is reinforced, and particularly along its leg portions 16b. That is as shown, a centrally-disposed vertical flange projects upwardly from a horizontal flange and extends from the loop frame 16a, outwardly along the full length of each leg portion 16b, as well as along and up to the end of the turned-down latching end 16c.

Referring particularly to FIGURES 4 to 9, inclusive, I have illustrated refractory hangers 17 which are employed, as shown in FIGURES 1 to 3, inclusive, to latch with and suspend a group, for example four, refractory brick or tile members 26 (see FIGURE 10). It will be noted that each refractory hanger tile 17 extends in the direction of an associated cross slide beam member 12 and that each hanger tile is suspended by a pair of metal hangers 13 that latch within their latching end or slot portions 19, see particularly FIGURE 2. As shown in FIGURE 2, the refractory hangers 17 are of a sufficient length, for example about twelve inches, to extend fully across and slightly beyond the bottom flange of the support beams 11, so that they may be hung at their opposite ends from hangers 13 that are carried by end portions of a pair of adjacent, longitudinally-aligned, relatively short length cross beams 12 of a given row such as A or C. It may be noted at this point that, although in FIGURE 1, I have illustrated rows A and C as directly supported from the cross beam members 12 and the row B as indirectly supported from an adjacent pair of such members 12 by means of metal link bars 16 which simplifies the construction and minimizes the amount of metal required and importantly provides top access for patching, that without departing from the spirit and scope of my invention, intermediate rows B may be supported in the same manner as the rows A and C, thus eliminating the use of link bars 16, but requiring additional cross beams 12 and cooperating sets or row pairs of metal hangers 13.

Again referring to FIGURES 4 to 9, inclusive, the refractory hanger 17 has a somewhat narrow top face 17a whose width, as shown in FIGURE 3, substantially corresponds to the width of the bottom flange of an associated cross beam member 12. The refractory hanger 17 also has a somewhat narrow bottom face 17b which is adapted to pivotally suspend a group of refractory tile or brick 26 in an endwise-aligned relation with each other, see particularly FIGURES 2 and 3. The refractory hanger 17 also has opposed pairs of substantially planar edge or end faces 17e and 17f. Top notches or slots 18 are shown in the top face 17b that are open to the opposite sides 17c and 17d and have a spaced relation therealong to normally cooperate with the latching end portions 16c of link bars 16, and to receive and support the portions 16c (see FIGURE 15) between hangers 13 when the roof is being patched. Opposite top end portions of the refractory hanger 17 have half slots 18a that are also open to their ends to define a full slot with like half slots of an adjacent abutting and endwise-aligned refractory hanger.

Cross-extending, horizontal latching slot portions 19 are open through upper portions of the end faces 17e and 17f and extend between front and back side faces 17c and 17d. It will be noted that the slots 19 have inwardly-enlarged or offset latching key portions to receive a bottom connecting or cross portion 13b of the metal hangers 13. As shown in FIGURE 3, the portion 13b is adapted to be entered from the end face 17e or 17f, as the case may be, to swingably suspend the refractory hanger 17 adjacent its end. It will be noted that a pair of the metal hangers 13 suspend each refractory hanger 17.

One side (front) face 17c of the refractory hanger 17 has a set of inwardly-offset latching grooves, depressions or slots 20 that are closed-off by an inwardly-offset hori-

zontal bottom rib, rim or flange portion 21. The flange portion 21 as well as intermediate vertical rib portions 22 and end rib portions 22a, the latter of which are on the same vertical plane as the flange portion 21, define or enclose the slots 20 their bottom and vertical sides. A downwardly-inwardly declining intermediate pivot surface 23, see particularly FIGURE 9, defines the upper boundary for the slots 20. The opposite side (back) face 17d of the tile or refractory hanger 17 is provided with spaced-apart latching grooves or slots 24 constituting back grooves which are beveled or sloped downwardly-inwardly towards the bottom face 17b and are defined by downwardly-inclined adjacent tongues 25. It will be noted that the latching grooves 24 are transversely-aligned with respect to the latching slots, depressions or grooves 20 on the opposite or front face 17c.

Referring particularly to FIGURES 10 and 11, I have shown refractory block or tile 26 that have latching slot portions centrally-disposed within and open to their top ends or faces, so that they may be carried in a suspended and aligned relationship as groups by the refractory hanger 17 which is pivotally inserted within (see FIGURE 3) and is retained in a latched relation within the open slot portions of the refractory tile. Each tile 26 has relatively narrow top and bottom faces or ends 26a and 26b, relatively wide vertical side faces 26c and 26d, and relatively narrow vertical side or edge faces 26e and 26f. An upwardly-open top latch or latching slot portion 27 has an offset inner portion, as defined by an upper pivot ledge 27a, to guide it into a complementary fitting relation with in the slots 20 of the pivot latching nose of the refractory hanger 17. The pivot ledge 27a has opposed, inwardly-offset side faces and an upwardly-beveled or sloped nose face, see particularly FIGURE 11, for also facilitating its entry into one of the slots 20. A centrally-disposed, vertical, rectangular rib 27b in an opposed relation to the pivot ledge 27a is of a width corresponding to the width of the grooves 24 (see FIGURES 8 and 9) of the refractory hanger 17 and is adapted to slide into one of such grooves along a pair of adjacent and spaced-apart tongues 25. The portion 27b terminates in a vertical, inwardly-beveled or sloped face or bottom portion 27c that extends therefrom into the bottom or base of the latching slot 27. The vertical portion 27b acts as a guide surface for the beveled bottom portions of the grooves 24 of the refractory hanger 17, see FIGURE 3.

The tile 26 (see FIGURES 10 and 11) is provided with downwardly-outwardly sloped top edge portions 28 and a plurality of vertically spaced-apart, substantially horizontally-extending, alternate, interlatching or interlocking horizontal cross slots 30 and ribs 29 (tongue and groove portions) along each of its edge or narrow side faces 26e and 26f. It will be noted that the cross tongue and grooves of one edge or narrow side face 26e are vertically staggered with respect to those on the opposite edge or narrow side face 26f. In this manner, a complementary interfitting relationship is accomplished between adjacent abutting tiles 26 of longitudinally adjacent rows of tiles that are suspended as transversely-edge or narrow side aligned groups, such as rows A and C of FIGURE 1 by their respective refractory hangers 17, or such as row B by the link bars 16. As shown in FIGURE 3, the tiles 26 are carried or suspended in such a manner that their wide side faces 26c and 26d abut in a given row and that their edge or narrow side faces 26e and 26f interlock with complementary edge or narrow side faces of the tile of adjacent abutting rows. As shown in FIGURE 1, the tile 26 of adjacent rows are mounted in an alternate overlapping relation (for example, with a one inch overlap) with respect to each other. This, with tongue and groove portions 29 and 30, provides a bonded construction. I have thus been able to eliminate tongue and groove connections between adjacent abutting tiles 26 of the brick rows and, at the same time, employ a better and simplified type of tile having smooth or planar side faces 26c and 26d. In

5 this way, I obtain an effective interlock between the tile, blocks or bricks 26 by using adjacent tile to bridge them.

As shown in FIGURE 14, where the end tongues and grooves 29 and 30 of a pair of tile are of the same positioning and do not complement each other, as may occur when dividing up the building of the roof into two opposed side halves, whose tile members are pivoted into a latch-hanging position from opposite directions, the centerline voids of reversed starting tile may be filled with mortar 31. When closing-up the last row of a tile wall or in replacing burnt-out tile, it may be advantageous to provide refractory hangers 17' (see FIGURE 17) of modified construction. They may be made of shorter length, for example of half size, as illustrated in FIGURE 17, and 10 with top face slots (18 and 18a) as well as end ribs (22a) omitted. In addition, the latching slot 19' may be further lengthened or extended horizontally from one end of the tile 17', in order to permit the lower bar or cross portion of the central loop 16a of the link hanger 16 to enter 15 further therealong, see FIGURE 15 taken in view of FIGURES 16 and 17. The refractory hangers 17' are preferably made slightly shorter in height than the hangers 17 of FIGURE 16, in order to compensate for the slots 18 and 18a of the refractory hangers 17 and lie substantially flush along their bottom faces with respect to the hangers 17.

When repairs are being made to a roof, the latching ends 16c of the cross links 16 may rest directly in notches 30 such as A and C of FIGURE 1, and as shown as to rows D and F of FIGURE 15. The bottom shelf portions 15 of the metal hangers 13 and the tongues 25 of the last refractory hanger tile 17' may be cut-off to facilitate dropping the final unit in from the top.

35 Row H of FIGURE 18 and FIGURE 20 illustrates the use of the modified refractory hangers 17'. In FIGURES 19 and 21, I have shown a modified type of metal hanger 13', whose portions that are somewhat similar to the portions of the hanger of FIGURE 12 have been 40 given prime affixes, but the same reference numerals. In this connection, the ledge portions 15' have a slightly different shape, in that they are substantially rectangular in their extension.

FIGURE 19 shows that the ledge portions 15' of an 45 adjacent pair of metal hangers 13' may be positioned to project in opposite directions, instead of the same direction, as shown in the arrangement of FIGURE 2 as to the shelf portions 15. It is thus apparent that the inventive structure may be modified to meet particular conditions without departing from the invention, and that the 50 parts employed are flexible in their adaptability to particular requirements, for example, to repair work in replacing individual or groups of refractory block or in closing-up the last row of a roof.

55 Referring again to FIGURES 1, 2 and 3, a series of refractory tile 26 are hung from each refractory hanger 17 as an aligned group or row. The refractory hangers 17 of one row are positioned in an endwise-aligned and closely-adjacent relation with each other, so that the tile 26 carried thereby are carried in a close, sidewise-abutting, sealed relationship in such row. As particularly illustrated in FIGURE 2, the wide side faces 26c and 26d of the tile of each row and of each refractory-hung group in a row are in a closely abutting relationship and extend along in the same direction or parallel to the cross beam member 12 which supports them. The tile 26 of the intermediate row B of FIGURE 1 have the same relationship, except that they have an inwardly-spaced, central positioning with respect to an adjacent pair of cross beams 12.

60 The refractory hangers 17 are, in turn, supported or suspended at their opposite narrow vertical ends by a spaced, adjacent pair of metal hangers 13, and the latter are slidably suspended from a cross beam 12 which is a secondary or slide beam from the standpoint of a pair

of fixed beams 11. The intermediate row B, instead of being carried directly by the metal hangers 13, is directly carried by link bars 16, whose central loops 16a normally align with the sidewise-open slot portions 18 and 18a of the refractory hangers 17, and the latching ends 16c of whose arms are adapted to rest upon members of the directly suspended rows A and C. The link bars 16 thus support or suspended their block row (see row B of FIGURE 1) indirectly from an adjacent pair of cross beam members 12.

It will be noted that, in a normal construction, such as represented by FIGURES 1 to 13, inclusive, the latching ends 16c of the link bar 16 cooperate with the shelf or ledge portions 15 of the hangers 13 as well as with top slots 18 and 18a in the top faces of the refractory hangers 17. In the construction of FIGURE 16 employed for patching or repair work, the last refractory hanger row to be replaced will be made an intermediate row (such as E), and the ends 16c of the link bars 16 will then rest within side slots 18 and 18a of the refractory hangers 17 of adjacent rows D and F. The last or closing row of tile of the refractory hanger row E, as employed in closing up the hole, have to be slid down into position. Thus, I chip off their tongues 30, since they can't be pivoted into position in the manner of FIGURE 3; it will be noted that refractory hangers 17' are used for the row E. Mortar may be used between end face voids of the last or closing row of tile of the refractory hanger row E and adjacent abutting tile rows.

In the modified construction of FIGURES 18 and 19, the link bars 16 rest at their latching ends 16c on the shelf portions 15' of the modified hangers 13' and no top slots are used in the refractory hangers 17' (see also FIGURE 17). In the case of the hangers 13 as well as the hangers 13', the side portions 13c and 13d or 13'c and 13'd lie closely along opposed side faces of the refractory hanger 17 or 17', so as to give a stable and guided, suspended relationship with such hangers. FIGURES 2 and 19 show that the metal hangers may be mounted so that shelf portions of adjacent pairs may either extend in one direction along a refractory block row or in an opposed direction with respect to each other along such a row.

Referring to the novel form of mounting of the tile 26 with respect to the refractory hangers 17 of FIGURE 3, it will be noted that the tile can only be engaged and disengaged by a pivoting or swinging action with respect to the refractory hangers. The overlapping portions or shoulders of the bottom pivot-latching portion of the hangers 17 and of the top pivot-latching portion of the associated tile members 26, assures a positive engagement that cannot be lost while the tile rows are in an abutting relation with each other. The so-called cross beams 12 that are of a relatively short length, as to their endwise rows, take the place of continuous-length longitudinal roof structural members. In their sidewise slidably-mounted relation on the support beams 11, the cross beams 12 greatly facilitate roof construction and repair and, as a row, carry a row of metal hangers 13 and of refractory hangers 17. Refractory, as employed herein with reference to the hangers 17 and 17' and the tile members, brick or block 26, is best defined in the Fifth edition of The Condensed Chemical Dictionary, Arthur and Elizabeth Rose, 1956, Reinhold Publishing Corporation, to the effect that it is a nonmetallic structural material for use at high temperatures; it thus includes ceramic materials.

What I claim is:

1. In a furnace roof construction having spaced-apart support beams, a group of cross beams carried by the support beams, metal hangers carried by the cross beams, refractory hangers of nonmetallic structural material carried by the metal hangers, and refractory tile carried by the refractory hangers, an improved suspension assembly wherein, the cross beams are liftably-off and slidably-

positioned at their opposite ends to rest upon opposed flanges of adjacent pairs of the support beams to extend across therebetween, each metal hanger has a unitary-closed loop slidably positioned on the top flange of an associated cross beam to project downwardly therefrom, each refractory hanger has slot portions, and a pair of the metal hangers are positioned on an associated cross beam to engage within the slot portions of an associated refractory hanger.

10. 2. In a furnace roof construction having spaced-apart support beams, a group of cross beams carried by the support beams, metal hangers carried by the cross beams, refractory hangers of nonmetallic structural material carried by the metal hangers, and refractory tile carried by the refractory hangers, an improved suspension assembly wherein, the cross beams are positioned at their opposite ends to rest upon bottom flanges of adjacent pairs of the support beams to extend across therebetween and be liftable therefrom, each metal hanger has a unitary-closed 15 loop shape and has a top link portion slidably positioned on the top flange of an associated cross beam to suspend said hanger downwardly along the associated cross beam and therefrom, each refractory hanger has end slots, and a pair of said metal hangers are positioned on an associated cross beam and have bottom link portions to engage within the end slots of an associated refractory 20 hanger.

3. In a furnace roof construction having spaced-apart support beams, a group of cross beams carried in a spaced-apart relation by the support beams, metal hangers carried by the cross beams, refractory hangers of nonmetallic structural material carried by the metal hangers and having latching slot portions, and refractory tile carried by the refractory hangers, an improved suspension 35 assembly wherein, the metal hangers are carried as hanger rows in suspension from the cross beams, the metal hangers carry the refractory hangers as aligned rows therebeneath, metal link bars are positioned between adjacent rows of the metal hangers and have central loop portions latch-engaging within the latching slot portions of the refractory hangers to suspend a row of refractory hangers in alignment therefrom, and said link bars have 40 arms resting upon the metal hangers of the adjacent rows along the cross beams for support thereon.

4. In a furnace roof construction as defined in claim 3 wherein, the metal hangers are of closed-loop construction and have projecting shelf portions, and the arms of the said link bars latch on said shelf portions of adjacent rows of the metal hangers.

5. In a furnace roof construction having spaced-apart support beams, a group of cross beams carried in a spaced-apart relation by the support beams, metal hangers carried by the cross beams, refractory hangers of nonmetallic structural material carried by the metal hangers, and rows of refractory tile carried by the refractory hangers, an improved suspension assembly wherein, the metal hangers are slidably positioned along the cross beam members and suspend refractory hangers therefrom as aligned rows therewith, the refractory hangers have 55 side-mounted open latching slot portions, link bars are provided having vertical central loop portions that engage within the latching slot portions of and suspend the refractory hangers as an intermediate row between an adjacent pair of the aligned rows, and said link bars have 60 side-mounted open latching slot portions, link bars are provided having vertical central loop portions that engage within the latching slot portions of and suspend the refractory hangers as an intermediate row between an adjacent pair of the aligned rows, and said link bars have 65 arms projecting from their central loop portions to cooperate with and engage the metal hangers of the aligned rows of the adjacent pair to suspend said link bars therefrom.

6. In an improved hanger for carrying a refractory hanger of nonmetallic structural material of a furnace roof construction, a unitary metal closed loop frame defined by opposed horizontal top and bottom link portions and opposed vertical side portions, and a pair of guide shelf portions projecting in one direction from the side 70 75

portions perpendicular to the plane of said loop frame to guide the refractory hanger therebetween.

7. In an improved metal hanger for positioning over a cross beam member of a furnace roof construction, a unitary metal closed-loop frame defined by opposed horizontal top and bottom horizontal link portions and opposed vertical side portions, said loop frame being constructed to fit over the cross beam member, horizontal top position-stabilizing tab portions projecting in opposite directions from said top link portion substantially perpendicular to the plane of said frame to rest upon the top flange of the cross beam member and extend in the direction of its length to prevent said frame from swinging in either direction on the associated cross beam member, and a pair of guide shelf portions projecting from the side portions perpendicular to the plane of said loop frame to guide the refractory hanger therebetween.

8. An improved metal hanger for carrying refractory hangers of a furnace roof construction from a pair of spaced-apart adjacent supports, said hanger being provided with a metal link bar having a vertical centrally-disposed closed loop frame projecting downwardly therefrom and having its top loop defined by said link bar, said link bar defining a pair of arms projecting from opposite sides of the top loop of said loop frame, turned-down latching ends on the projecting portions of said arms to suspend said link bar from the pair of spaced-apart adjacent supports, a bottom loop of said loop frame being constructed to slidably engage within and suspend the refractory hangers therefrom, and said pair of arms being reinforced by an upwardly-projecting flange that extends centrally-longitudinally therealong and along said turned-down latching ends.

9. In an improved refractory tile for a furnace roof construction that is adapted to be suspended by a refractory hanger, a refractory body having opposed relatively narrow substantially planar top and bottom faces, opposed relatively wide vertical and substantially planar side faces, and relatively narrow vertical opposed side faces provided with substantially horizontal tongue and groove portions vertically disposed therealong; the tongue and groove portions of one narrow vertical side face being staggered with respect to those of the other narrow vertical side face, so that a pair of adjacent tile may be positioned in a complementary interfitting relationship as to their adjacent narrow side face portions, said body having a substantially centrally-disposed upwardly-open top latching-slot portion extending downwardly from its top face to receive the refractory hanger for suspension therefrom, said slot portion being vertically-open to said top face and being horizontally-open to said opposed planar side faces; said slot portion being defined by an upwardly-beveled nose face projecting therein, a recess beneath said nose face, and an opposed vertically-extending centrally-disposed rib defining a narrow entry opening with said nose face, and said rib terminating in an inwardly-beveled face extending into said recess for defining a guide surface.

10. In an improved refractory hanger for suspension from a cross member of a metal hanger and for carrying a group of refractory tile members in a suspended relation therefrom, a refractory body of nonmetallic structural material having relatively wide opposed side faces and relatively narrow end faces, a pivot latching nose portion projecting upwardly from a bottom face of said body to carry the tile members in a latched-on suspended relation therefrom, at least one horizontal latching slot portion extending from an end face of said body along and open to the opposed side faces thereof to receive the cross member of the metal hanger therein, and said nose portion being defined by a substantially vertical planar portion of one of said opposed side faces and a portion inwardly-beveled therefrom into a bottom end face of said body, and said refractory body has an inwardly-

offset lower planar vertical face below the other of said opposed side faces and connected thereto by vertical ribs that define substantially closed-end rectangular latching recesses.

- 5 11. In a furnace roof construction having longitudinal rows of cross beams in a spaced-apart relation, refractory hangers of nonmetallic structural material having opposed side faces and opposed narrow side faces, and refractory tile members carried by the refractory hangers, an improved suspension assembly wherein, the refractory hangers are carried by the cross beams with their opposed narrow side faces in substantial longitudinal alignment with the cross beams, the refractory tile members have top and bottom ends and opposed narrow side faces and substantially planar opposed wide side faces and are suspended by each refractory hanger as a group with their opposed wide side faces substantially at right angles to the opposed wide side faces of the associated refractory hanger and in a longitudinal row with their planar wide side faces in 10 abutment with each other to define adjacent longitudinal rows substantially parallel to the longitudinal rows of the cross beams, refractory tile members of the adjacent longitudinal rows have interlatching tongue and groove joints with respect to each other along their opposed narrow 15 side faces to lock the rows in position with respect to each other, each refractory tile member has a latching slot portion centrally-disposed within and open to its top end, the refractory hangers have tongue and groove portions along their opposed wide side faces that engage in a complementary manner within said latching slot portions of a group of the tile members of an associated longitudinal row to individually lock and suspend the tile members of the associated longitudinal row in position with respect to each other therealong, and the latching slot portion of each 20 refractory tile member has a shoulder cooperating with the tongue and groove portions of an associated refractory hanger for pivotally-mounting refractory tile members on the associated hanger independently of transversely adjacent refractory tile members.
- 25 12. In a furnace roof construction having longitudinal rows of cross beams in a spaced-apart relation therealong, an improved suspension assembly wherein, hangers are suspended from and slidably along the cross beam rows, longitudinal rows of refractory members of nonmetallic structural material are suspended by said hangers in a slid- 30 able relation along the cross beam rows, hanger bars rest upon and extend across between adjacent pairs of the refractory members of the cross beam rows and are liftably-suspended on said hangers, said hangers suspend a refractory member row from each of the cross beam rows, and said hanger bars have central loop portions that latch- 35 engage within the refractory members of and suspend at least one refractory member row between refractory member rows that are suspended by adjacent cross beam rows.
- 40 13. In a furnace roof construction having spaced-apart support beams, a group of cross beams carried by the support beams, metal hangers carried by the cross beams, and refractory members of nonmetallic structural material carried by the metal hangers, an improved suspension assembly wherein, the cross beams are slidably and swingably-liftable positioned at their opposite ends to rest upon the bottom flanges of adjacent pairs of the support beams to extend across therebetween, each metal hanger has a unitary-closed loop-shaped portion that is slidably- 45 positioned on the top flange of an associated cross beam to project downwardly therealong and therefrom, the refractory members have open-side latching slot portions, and said loop-shaped portions of the metal hangers are constructed to transversely-enter and detachably latch- 50 engage within said latching slot portions of the refractory members to suspend them from the cross beams.
- 55 14. In a furnace roof construction having spaced-apart support beams, a group of cross beams carried by the support beams in a spaced relation with respect to each other, metal hangers carried by the cross beams as cross beam 60

rows, refractory hangers of nonmetallic structural material carried by and along the metal hangers as refractory hanger rows, refractory tile carried by the refractory hangers of the metal hanger rows, and intermediate rows of refractory hangers along and between adjacent pairs of the metal hanger rows, an improved suspended assembly wherein, the cross beams are slidably-positioned at their opposite ends to rest upon bottom flanges of adjacent pairs of the support beams to extend across therebetween, the metal hangers of the cross beam rows are slidably suspended from the top flanges of the associated cross beams to project downwardly therealong and therefrom, metal link bars are provided having vertical centrally-disposed portions for carrying the intermediate rows of the refractory hangers substantially parallel to adjacent rows of the refractory hangers that are carried by the metal hangers, said metal link bars having side-projecting arms to rest upon and suspend them from and between adjacent rows of the refractory hangers, each refractory hanger has a nose-shaped bottom latching portion provided with a group of adjacent opposite pivot portions, each refractory tile has a top latching-slot portion to engage within one of said pivot portions of an associated refractory hanger, so that a group of refractory tile may be suspended from each refractory hanger, each refractory hanger has end slots therein, the refractory hangers of the metal hanger rows are suspended by engagement of adjacent pairs of the metal hangers within said end slots, said metal link bars having central loop portions, and the refractory hangers of the intermediate rows are suspended by engagement of said central loop portions of said metal link bars within said end slots.

15. In a furnace roof construction, securely-horizontally - positioned transversely - spaced - apart longitudinal support beams having bottom flanges projecting from opposite sides thereof; a group of horizontal spanning cross beams, each having a top flange and having a bottom flange projecting from opposite sides thereof and resting upon the bottom flanges of adjacent pairs of said longitudinal beams and extending across therebetween for slideable movement therealong; metal hangers carried in a vertically-suspended relation by said cross beams; refractory hangers of nonmetallic structural material carried in a vertically-suspended relation by said metal hangers in rows along said cross beams, refractory tile carried in a vertically-suspended relation by said refractory hangers, and each of said cross beams being positioned with its bottom flange on opposite bottom flange portions of an adjacent pair of said longitudinal beams in such a manner that it may be lifted out of position at one end with respect to one of said longitudinal beams by pivoting its one end on the bottom flange portion of the other of said longitudinal beams; each of said metal hangers is of loop shape, has an upper connecting link portion resting on the top flange of an associated one of the cross beams, has a pair of vertical side portions projecting downwardly along the associated cross beam, has a bottom connecting link portion that detachably engages within an associated one of said refractory hangers, and has a pair of shelf portions projecting substantially horizontally from said vertical side portions above said bottom connecting link portion to slidably guide the associated refractory hanger into and hold it in a detachably-engaging relation with said bottom connecting link portion.

16. In a furnace roof construction, securely-horizontally - positioned transversely - spaced - apart longitudinal support beams having bottom flanges projecting from opposite sides thereof; a group of horizontal spanning cross beams, each having a top flange and having a bottom flange projecting from opposite sides thereof and resting upon the bottom flanges of adjacent pairs of said longitudinal beams and extending across therebetween for slideable movement therealong; metal hangers carried in a vertically-suspended relation by said cross beams, refractory hangers of nonmetallic construction material carried

in a vertically-suspended relation by said metal hangers in rows along said cross beams, refractory tile carried in a vertically-suspended relation by said refractory hangers, and each of said cross beams being positioned with its bottom flange on opposite bottom flange portions of an adjacent pair of said longitudinal beams in such a manner that it may be lifted out of position at one end with respect to one of said longitudinal beams by pivoting its other end on the bottom flange portion of the other of said longitudinal beam; each of said metal hangers being slidably positioned on the top flange of and about an associated one of said cross beams for endwise movement therealong and having a portion suspended downwardly therefrom and engaging within an associated refractory hanger; each of said metal hangers being of unitary closed-loop shape and having an upper connecting link portion slidably resting upon the top flange of an associated one of said cross beams, having a pair of vertical side portions projecting in a spaced relation downwardly along the associated cross beam and past the bottom flange thereof, and having a bottom connecting link portion that constitutes the portion suspended downwardly thereof and that detachably engages within an associated one of said refractory hangers; and each of said metal hangers having a pair of shelf portions projecting substantially horizontally from said vertical side portions above said bottom connecting link portion to slidably guide the associated refractory hanger into and hold it in its detachable engaging relation with said bottom connecting link portion.

30 17. In a furnace roof construction having longitudinal rows of cross beams in a spaced-apart relation, refractory hangers of non-metallic structural material having opposed side faces and carried by the cross beams, and refractory tile members carried by the refractory hangers, an improved suspension assembly wherein, the refractory tile members have top and bottom ends and opposed narrow side faces and substantially planar opposed wide side faces and are suspended by each refractory hanger as a group in a longitudinal row with their planar wide side faces in abutment with each other to define adjacent longitudinal rows substantially parallel to the longitudinal rows of the cross beams, refractory tile members of the adjacent longitudinal rows have interlatching tongue and groove joints with respect to each other along their opposed narrow side faces to lock the rows in position with respect to each other, each refractory tile member has a latching slot portion centrally-disposed within and open to its top end, the refractory hangers have tongue and groove portions along their opposed side faces that engage in a complementary manner within said latching slot portions of the tile members of an associated longitudinal row to individually lock and suspend the tile members of the associated longitudinal row in position with respect to each other therealong, and said latching slot portion of each refractory tile member has a shoulder cooperating with a tongue portion of an associated refractory hanger and is constructed to require the tile member to be pivotally inserted on the associated refractory hanger and to retain the refractory tile member in a suspended relation on the tongue portion.
